TOI Basin Mixer, Phoenix Tapware, Showers & Accessories, <http://www.phoenixtapware.com.au/products/toi-basin-mixer>, known at least as early as Oct. 25, 2016, 3 pgs.

(Continued)

Primary Examiner — Karen S Acker*Assistant Examiner* — Elizabeth S Ko(74) *Attorney, Agent, or Firm* — Womble Bond Dickinson (US) LLP(57) **CLAIM**

The ornamental design for a hand shower bracket, as shown and described.

DESCRIPTION

FIG. 1 is an isometric front view of a hand shower bracket according to our new design;

FIG. 2 is an isometric rear view thereof;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a rear view thereof.

The portions of the hand shower bracket shown in evenly-spaced broken lines form no part of the claimed design.
